UNITED STATES PATENT OFFICE.

JOSEPH L. HERZOG, OF NEW ROCHELLE, NEW YORK.

DESIGN FOR A FINGER RING OR SIMILAR ARTICLE.

Application filed May 28, 1926. Serial No. 17,874. Term of patent 14 years.

To all whom it may concern:

Be it known that I, JOSEPH L. HERZOG, a citizen of the United States, and resident of New Rochelle, county of Westchester, State of New York, have invented a new, original, and ornamental Design for a Finger Ring or Similar Article, of which the following is a specification.

In the accompanying drawing forming a part of this specification is shown a ring of octagonal top and provided with a diamond of the round type, and Fig. 1 is a top view of a ring embodying the design, and Fig. 2 is a side view thereof. In the drawings, the central part of Fig. 1 and the top of Fig. 2

depicts a diamond with its customary facets, the diamond being mounted in the ring structure. The diamond and the element used for its mounting are surrounded by a tapering band of gray or platinum color, acutely engraved producing a glittering effect which co-operates with the glitter of the diamond and vice versa producing a composite design resembling a diamond set in a surrounding field of small diamonds.

I claim:

The ornamental design for a finger ring or similar article substantially as shown and described.

JOSEPH L. HERZOG.
